SEMAUTOMATIC WASHER FOR VEHICLES OR THE LIKE

George W. Phillips and William C. Hitt, Los Angeles,
and Stephen M. Slonenger, San Fernando, Calif., as-
signors to San Fernando Air Parts, Inc., San Fernando,
Calif., a corporation of California

Filed May 1, 1968, Ser. No. 11,728

Term of patent 14 years

Int. Cl. D15—07
U.S. Cl. D49—12

FIG. 1

FIG. 3

FIGURE 1 is a front perspective view of a semiautomatic washer for vehicles or the like, showing our new design;

FIGURE 2 is a fragmentary rear perspective view thereof;

FIGURE 3 is a fragmentary front elevational view thereof;

FIGURE 4 is an enlarged fragmentary front elevational view thereof;

FIGURE 5 is an enlarged fragmentary side elevational view thereof, the other side being a mirror image thereof;

FIGURE 6 is a fragmentary rear elevational view thereof; and

FIGURE 7 is a fragmentary top plan view thereof.

The support pole, hose and nozzle elements are frag-

mentarily shown in FIGURES 2-7 for convenience of illustration.

We claim:

The ornamental design for a semiautomatic washer for vehicles or the like, substantially as shown and described.
